UNITED STATES PATENT OFFICE.

EDWARD P. FRAWLEY, OF NEW YORK, N. Y.

DESIGN FOR A DESK-CABINET.

52,787.

Specification for Design.

Patented Dec. 24, 1918.

Application filed August 15, 1918. Serial No. 250,082. Term of patent 14 years.

To all whom it may concern:

Be it known that I, EDWARD P. FRAWLEY, a citizen of the United States, and a resident of the city of New York, borough of Manhattan, in the county and State of New York, have invented a new, original, and ornamental Design for a Desk-Cabinet, of which the following is a specification, reference being had to the accompanying drawings, forming part thereof.

Figure 1 is a perspective view of a desk cabinet showing my new design, the lid of the cabinet being open; and

Fig. 2 is a plan view.

I claim:

The ornamental design for a desk cabinet, as shown.

EDWARD P. FRAWLEY.
